CLAIM

The ornamental design for a display panel or a portion thereof with a graphical user interface, as shown and described.

DESCRIPTION

FIGURE is a front view of a display panel or portion thereof with a graphical user interface according to an example embodiment of the design.

The outer broken line illustrates a display panel or a portion thereof and forms no part of the claimed design. The remaining broken lines illustrate portions of the graphical user interface and form no part of the claimed design.

1 Claim, 1 Drawing Sheet
